Attorney

UNITED STATES PATENT OFFICE

JEROME WIESMAN, OF DENVER, COLORADO

GARMENT DRIER

Application filed March 22, 1929. Serial No. 349,017.

This invention relates to an apparatus for drying and aerating garments after they have been dry cleaned. Some of the solvents used in dry cleaning must be used cold and if the garment is heated to dry the solvent it will result in ruining the colors. Other solvents can and should be dried by the application of heat. The principal object of this invention is to provide a device by means of which garments may be subjected to either a hot or cold air blast or a mixture thereof, so that the drying can be suited to the type of solvent employed.

In some cases it is desirable to dry the garment slowly and remove the evaporating solvent therefrom. Another object of this invention is to provide a mechanism in which the garments can be subjected to a suction so that the evaporating solvents will be rapidly removed from the vicinity of the garments.

A further object of this invention is to so construct the device that an air blast can be introduced into the interior of the garments so that they will be stretched while drying so as to prevent shrinkage, wrinkling and crushing.

A still further object of this invention is to so construct the device that a relatively small door can be employed for placing and removing all of the garments which are contained within the device, so that loss of heat and escape of solvent fumes will be reduced to a minimum.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in the drawing and throughout the description.

The drawing illustrates a perspective view

of the invention partially broken away to show the interior construction thereof.

The invention comprises a housing 10, provided with a door 9 and an exhaust stack 11. Vertically within the center of the housing 50 10 a post or standard 12 is fixed, upon the upper extremity of which a garment wheel 13 is free to rotate. A circular floor plate 14 is suspended from the garment wheel 13 upon suitable hanger bars 15 so that it will be rotated in unison with the garment wheel 13 about the standard 12.

The floor plate 14 is provided with a series of openings 16, each surrounded by an up-standing flange 17. Around each of the 60 flanges 17 a series of spring clips 18 are secured to the floor plate 14. Each of the openings 16 is provided with a cap 19 which engages the flange 17 to close the opening when desired. The floor plate 14 is suspended 65 above the floor of the container 10 to form a heating chamber in the base of the housing 10. A steam coil 20 is placed within the heating chamber and is provided with a suitable steam valve 21 and discharge 22.

Alongside of the container 10 is a fan chamber 23, provided with any suitable design of fan 24, operated by means of an electric motor 25. The fan chamber 23 is open to the interior of the container 10, as shown at 26, 75 below the floor plate 14. The opening 26 can be controlled by means of a slide 27 which is supported in any desired position by means of a counter weight 28.

The counter weight 28 is secured to the 80 slide 27 by a suitable chain 29 which passes over pulleys 30 secured to the housing 10.

An air by-pass pipe 31 extends from the top of the fan chamber 23 upwardly into the stack 11. Within the stack the by-pass is 85 turned upwardly, as indicated in broken line at 32. The flow of air through the by-pass pipe 31 is controlled by means of a damper 33.

In use, the garments, such as indicated at 34, are placed directly over the openings 16 90

in the floor plate 14. The bottom of each garment is secured about an opening 16 by means of the spring clips 18 which engage the lower hem thereof. The garments are carried on the ordinary garment hangers, such as illustrated at 35. The hook of the hanger 35 is engaged in a chain 36 suspended from the garment wheel 13. By this arrangement the height of the hanger 35 can be adjusted so as to accommodate the length of the garment 34.

10 Each of the openings 16 may be covered by a garment but should there not be sufficient garments to cover all of the openings the remaining openings are maintained closed by 15 means of the caps 19, to prevent useless escape of the air from the heating chamber. The door 9 is now closed and latched.

20 Should the garments require a hot blast of air for drying, the steam valve 21 is opened to heat the steam coils 20. The damper 33 is closed and the slide 27 is opened so that the entire blast of the fan 24 will pass into the heating chamber. The heated air will 25 pass upwardly through the openings 16 into the interior of the garments 34 and discharge, through the stack 11. The amount of air can be controlled as desired by means of the slide 27.

30 Should only a cold blast be desired the steam coils 21 are turned off. If no blast is desired within the container a suction can be provided to remove the evaporating solvents by closing the slide 27 and opening the damper 33. This causes the entire blast from the 35 fan to discharge from the by-pass 31 into the stack 11. The upturned extremity 32 causes an ejector effect in the stack to draw air and fumes from the interior of the container 10. Of course, a combination of all these features 40 can be employed by proper manipulation of the steam valve 21, slide 27, and damper 33. Access to any desired garment can be quickly obtained by rotating the floor plate 14 to bring the desired garment before the door 9.

45 It has been found that after garments have been dried by the application of heat they have a scorched odor. This can be entirely removed in the present device by turning off the heat and subjecting the garments to a 50 blast of cold air.

55 While a specific form of the improvement has been described and illustrated herein, it is desired to be understood that the same may be varied, within the scope of the appended claims, without departing from the spirit of the invention.

Having thus described the invention, what I claim and desire secured by Letters Patent 60 is:—

65 1. A garment drier comprising: a vertical cylindrical housing; a garment wheel adapted to rotate in a horizontal plane within said housing; means for hanging garments from said wheel; and a circular floor plate suspend-

ed from said wheel and adapted to rotate therewith.

2. A garment drier comprising: a vertical cylindrical housing; a garment wheel adapted to rotate in a horizontal plane within said housing; means for hanging garments from said wheel; a circular floor plate suspended from said wheel and adapted to rotate therewith; and a heating chamber below said floor plate there being openings in said floor plate 70 to allow air from said heating chamber to pass therethrough.

3. A garment drier comprising: a vertical cylindrical housing; a garment wheel adapted to rotate in a horizontal plane within said housing; means for hanging garments from said wheel; a circular floor plate suspended from said wheel and adapted to rotate therewith; a heating chamber below said floor plate there being openings in said floor plate 80 to allow air from said heating chamber to pass therethrough; and means for closing 85 said openings as desired.

4. A garment drier comprising: a vertical cylindrical housing; a garment wheel adapted to rotate in a horizontal plane within said housing; means for hanging garments from said wheel; a circular floor plate suspended from said wheel and adapted to rotate therewith; a heating chamber below said floor plate there being openings in said floor plate 90 to allow air from said heating chamber to pass therethrough; and means for attaching garments about said openings; and a fan adapted to force air into said housing below said floor 95 plate.

5. A garment drier comprising: a vertical cylindrical housing; a garment wheel adapted to rotate in a horizontal plane within said housing; means for hanging garments from said wheel; a circular floor plate suspended from said wheel and adapted to rotate therewith; a heating chamber below said floor plate there being openings in said floor plate 105 to allow air from said heating chamber to pass therethrough; means for attaching garments about said openings; a fan adapted to force air into said housing below said floor plate; and a slide adapted to control the supply of air from said fan to said heating chamber.

6. A garment drier comprising: a vertical cylindrical housing; a garment wheel adapted to rotate in a horizontal plane within said housing; means for hanging garments from said wheel; a circular floor plate suspended from said wheel and adapted to rotate therewith; a heating chamber below said floor plate there being openings in said floor plate to allow air from said heating chamber to 110 pass therethrough; and a heating coil in said heating chamber.

7. A garment drier comprising: a vertical cylindrical housing; a vertical shaft positioned concentrically within said housing;

a garment wheel adapted to rotate in a horizontal plane upon the upper extremity of said shaft; a circular partition forming the top for a heating chamber in the bottom of said housing; hangers supporting said partition from said garment wheel so that it will rotate therewith, there being openings through said partition so that heated air may pass from said heating chamber to said housing at predetermined locations; and means for supporting garments from said garment wheel immediately over said locations.

In testimony whereof, I affix my signature.
JEROME WIESMAN.
